(57) **CLAIM**

The ornamental design for a baking pan with cover, as shown and described.

DESCRIPTION

FIG. 1 is a perspective view of the baking pan, shown without the cover for ease of illustration;

FIG. 2 is a left side elevational view of the baking pan without the cover, the right side elevational view being a mirror image thereof;

FIG. 3 is a front elevational view of the baking pan without the cover, the rear elevational view being a mirror image thereof;

FIG. 4 is a top plan view of the baking pan without the cover;

FIG. 5 is a bottom plan view of the baking pan without the cover;

FIG. 6 is a perspective view of the cover, shown without the baking pan for ease of illustration;

FIG. 7 is a left side elevational view of the cover for the baking pan, the right side elevational view being a mirror image thereof;

FIG. 8 is a front elevational view of the cover for the baking pan, the rear elevational view being a mirror image thereof;

FIG. 9 is a top plan view of the cover for the baking pan;

FIG. 10 is a bottom plan view of the cover for the baking pan; and,

FIG. 11 is an exploded view of the baking pan with the cover.
